United States Patent Office.

LOUIS EDOUARD RIVOT, OF PARIS, FRANCE, ASSIGNOR TO JACQUES GAILLARDON, OF SAN FRANCISCO, CALIFORNIA.

Letters Patent No. 73,839, dated January 28, 1868.

IMPROVED APPARATUS FOR AMALGAMATING GOLD AND SILVER ORES.

The Schedule referred to in these Letters Patent and making part of the same.

TO WHOM IT MAY CONCERN:

Be it known that I, LOUIS EDOUARD RIVOT, of Paris, in the Empire of France, have invented certain new and useful Improvements in the Method of and Means for Treating Auriferous and Argentiferous Ores; and I hereby declare the following to be a full, clear, and exact description of the same, reference being had to the accompanying drawings.

The present invention relates to an apparatus which may be used independently of the treatment to which argentiferous and auriferous ores are submitted, previous to the action thereon of the mercury. It is applicable to ore, whether treated by the methods now in use, or by the method for which Letters Patent of the United States were issued to me on the 31st of May, 1864, No. 42,997. The apparatus in question is represented in the annexed drawings, in which—

Figure 1 is a top view, and

Figure 2 is a sectional elevation on line 1 2, fig. 1.

The object sought to be attained by this invention is to bring all the grains of the ore into intimate and prolonged contact with the mercury, and this I accomplish by putting the ore with the mercury into the annular bed M, whose bottom is horizontal, and by causing to revolve therein, with more or less speed, vertical grinding-wheels or cylinders, R R' R'' R''', which are united by means of arms to a vertical shaft, S. Movement is imparted to the shaft by means of bevelled-gear wheels T, placed below the bed. This gear may be located, if convenient, above the apparatus, in which case the shaft should be longer, which is, however, always an objection. Upon the same shaft are mounted four arms, a b c d, which carry scrapers or knives, A B, and rakes, C D. The function of these knives is to bring to and under the wheels the matter which is carried into the angle of the angular bed, and the rakes serve to divide and separate from the bed the material compressed by the wheels.

The dimensions indicated in the accompanying drawings are those of an amalgamator for working three tons of ore at one time; they should be modified for apparatus which work larger or smaller quantities of ore. The apparatus shown is composed of four vertical wheels, two pairs of knives, and two rakes, for such, in my opinion, is the best arrangement for apparatus of the dimensions shown in the drawings. But I wish it to be expressly understood that the same result may be attained with two or three wheels, a single pair of knives, and but one rake.

The vertical shaft S is supported at its lower extremity in a suitable bearing, while higher up it is held in an annular bearing, which is maintained in proper position by means of a framework, as shown in fig. 2. The large bevelled-gear wheel T meshes with the pinion F, which is mounted on the arbor that receives rotary motion from some prime-mover. The relative size of the diameters of the two wheels must depend upon which movement from the prime-mover is to be transmitted to the vertical shaft. The speed of revolution of the vertical arbor S should vary from one to four or more revolutions per minute. The resistance which this arbor has to overcome being considerable, it is desirable to give the gear-wheel T a very large diameter, and to make the teeth of great solidity. The vertical arbor is of a rectangular section at its upper part, and carries a double cluster of sockets, G H, in which are secured the arms a b c d of the knives and rakes, and the arms of the four vertical wheels. The arms of the knives and rakes are immovably fixed in their sockets, and are united one with another, by means of rods, so as to prevent the arms from bending. The arms of the four vertical wheels are somewhat differently secured in their sockets.

On reference to fig. 2, it will be seen that, in order that the wheels may roll over matter of variable thickness, the arms are capable of a slight up-and-down play. The strain of the socket upon the arms, and of the arms upon the wheels, being considerable, these pieces should be made of great strength. The arms are united one to the other by means of rods, which will prevent the flexure of the arms, while allowing their up-and-down play.

The four wheels are cylindrical, and are like one another. Their felloes are twenty-five centimetres in length and two metres in diameter, and they are united to the hub by means of spokes, as those of a cart-wheel, or otherwise. They may be made of wood or iron, or of combined wood and iron; they may also be made of wood

and iron, with an iron rim, the essential point being that they should be cylindrical and of light weight, say one thousand kilogrammes per wheel. In their movement around the shaft S the wheels should revolve in different tracks. The distances from the inner edges of the wheels to the inner circle of the bed are respectively 0^m. 15, 0^m. 40, 0^m. 65, 0^m. 90. The wheel which is most distant from the vertical shaft S, is yet far enough from the exterior circle of the bed to allow the matter carried along with the wheel to drop within the bed, and not outside of it.

The knives A B are made of sheet or cast metal, and their connection with the arms α ϵ is shown sufficiently in fig. 2.

The rakes C D are similarly connected with their arms. Each rake carries from twelve to fourteen cutting-teeth, which are fixed to a somewhat inclined sheet-iron blade, which scrapes the bottom of the beds. The functions of these rakes are to divide up the matter rendered compact by the pressure over it of the vertical wheels.

The bed is composed of a horizontal annular floor, provided on the interior and exterior with flanges. It is supported by solid masonry, which is levelled with great care. The sole or bottom of the bed is formed of thick cast-iron plates. The lines of the joints radiate from a common centre, which is the axis of the shaft S. The plates form lap-joints, and are set closely together, so that the finest particles cannot pass between the plates. The surface of the sole should be smooth, so that the knives and rakes will encounter no obstacles in their rotary movement. The interior flange may be of cast or sheet iron; it rests against the masonry, and is united with the bottom plates by a groove-and-tenon joint. The outer flange, which is about forty centimetres in height, is formed of cast-iron plates, united together by bolts passing through ears cast on the outside, and they form a groove-and-tenon joint with the bottom plates, as shown in fig. 2. Moreover, an iron band or hoop on the outside completes the joint. The hoop may be composed of several sections, whose tension can be varied by means of screws and nuts. At one side the exterior flange is provided with a door, P, which slides in grooves. The door is supported by means of a frame, which also holds in place the sheet Q, which latter may be made of sheet or cast iron, and is inclined at an angle of about fifteen or twenty degrees.

The mass is removed from the amalgamating-bed, thoroughly mixed with water, and is dropped into the wooden receiver R, which is provided with a faucet at its lower end. The bottom of this receiver is inclined towards the faucet. The water which carries with it the divided mass issues from the receiver through the wooden channel U, by which it is carried to apparatus destined to collect the last particles of mercury. The receiver R is closed by means of a cover, which is provided with an opening surrounded with flanges u . These flanges prevent any of the matter being thrown out in descending through the chute.

The mode of operation is necessarily varied with the process which is adopted for the treatment of the ore. I shall confine myself to the description of the amalgamating, by mercury alone, of ore previously roasted by means of superheated steam. Two cases may occur: first, when the ore is brought to the amalgamator in the state in which it comes out from the furnace, that is, dry; second, when it becomes necessary to treat the ore roasted with superheated steam by means of water, in which case the ore is wet.

I. To amalgamate the dry ore, the operation is divided into three stages.

First stage. The sole of the annular bed is charged with such quantity of ore as can be conveniently amalgamated at one operation, with a quantity of mercury, say from thirty to forty parts of mercury to one part of gold or silver. The thickness of the layer of ore is from ten to fifteen centimetres. It is well, in charging the mercury, to disseminate it. The charge being completed, the wheels are put in motion, by giving them a speed of one or two revolutions per minute. It will be easy to judge if the proper speed of revolution is obtained, by inspecting the mercury at the expiration of about two hours. The mercury at this time should be so divided that its globules can no longer be distinguished. When the mercury is reduced to an impalpable state, and thus disseminated through the mass of the ore, the wheels are revolved for another two hours. Thus the first stage generally lasts four hours.

Second stage. Water is poured on the mass in fine streams by means of a rose, or otherwise, without stopping the wheels, which, however, are revolved but slowly. To ascertain when sufficient water has been added, the following indications are to be observed: The mass being a liquid paste, the mercury appears in small brilliant globules, but still remaining divided. With a larger or smaller quantity of water the mercury would agglomerate and form large globules or masses. Experience, however, will soon teach the quantity of water to be added and the speed with which the wheels should revolve for each particular kind of ore. When the requisite quantity of water has been added, the wheels are revolved from seven to eight hours, and water may be added from time to time, to retain the mass at the proper degree of consistency.

Third stage. When the amalgamation of the precious metal is completed, the mercury is to be gathered, and the gold and silver amalgams which have been formed are to be dissolved by it. There is introduced into the bed a quantity of water, sufficient to reduce the mass to a very liquid consistency; the wheels are then revolved very slowly for about three hours. During the discharging, the wheels are slowly revolved, and the door P is slightly raised, so that the mass may run out slowly into the receiver R, and thence into the conduit U. The whole mass is made to pass through the receiver, and all the parts of the amalgamator are thoroughly cleaned by water projected into it. When the washing of the apparatus is completed, the door is replaced, and the apparatus is ready for a new operation. The greater part of the mercury holding the amalgam in solution is collected in the receiver with a certain quantity of ore and water. At first the mercury is drawn off by opening the faucet, and is received into any suitable vessel, then, through the same faucet, the water and ore are let out and put in with the mass which passed out through the conduit U.

II. The wet ore. It is sometimes necessary to wash the ore, roasted by means of superheated steam, before submitting it to the action of mercury. In such cases the operation comprises the two last stages only. The

first stage, which may be called the dry trituration, is dispensed with, but it is necessary to increase the duration of the second stage to nine or ten hours. The mercury is divided somewhat more slowly than in the dry-amalgamating process, but this difficulty is compensated by the longer duration of the action of the mercury in the presence of water. Otherwise the operation is conducted in the same manner as hereinbefore indicated.

Having thus described my invention, what I claim, and desire to secure by Letters Patent, is—

The herein-described method of and apparatus for amalgamating auriferous and argentiferous ores.

In testimony whereof, I have signed my name to this specification before two subscribing witnesses.

L. E. RIVOT.
